[57] CLAIM

The ornamental design for a medallion, as shown and
described.

DESCRIPTION

FIG. 1 is a front-elevational view of a medallion showing
my new design;

FIG. 2 is a front-elevational view of a medallion showing
a second embodiment of my new design;

FIG. 3 is a cross-sectional view taken along the lines
3—3 of FIG. 1;

FIG. 4 is a cross-sectional view taken along the lines
4—4 of FIG. 1;

FIG. 5 is a top plan view; and,
FIG. 6 is a bottom plan view.

The cross-sectional and plan views are the same in both
embodiments. The rear-elevational view of each em-
bodyment is plain and unornamented.
